ATTORNEY

UNITED STATES PATENT OFFICE.

THOMAS LANGSTON, OF MERIDEN, CONNECTICUT, ASSIGNOR TO THE
EDWARD MILLER & COMPANY, OF SAME PLACE.

LANTERN.

SPECIFICATION forming part of Letters Patent No. 556,423, dated March 17, 1896.

Application filed July 20, 1895. Serial No. 556,648. (No model.)

To all whom it may concern:

Be it known that I, THOMAS LANGSTON, a citizen of the United States, residing at Meriden, New Haven county, Connecticut, have 5 invented a new and useful Improvement in Lanterns, of which the following is a specification.

My invention relates to that class of lanterns adapted to be used with an Argand or 10 other lamp requiring a central air-supply. It is intended to secure an equable supply of air to the flame under varying conditions of wind-pressure.

In the accompanying drawings, Figure 1 15 represents in elevation a lantern embodying my invention, the globe partly broken away to show the working parts. Fig. 2 is a vertical section of the lamp portion detached from the lantern. Fig. 3 is a top plan view of the 20 lamp only, the wind-guard being removed.

The same letters refer to like parts in the several views.

A designates a lantern-frame; A', a globe; B, an Argand lamp provided with inner air-supply tube b, vertical perforate flange b', horizontal flange b², air-tubes b³ and false bottom b⁴; C, a wind-guard consisting of curved portion c, vertical portion c' and flange c².

In the example of my invention illustrated 25 in the drawings the lantern frame or body A and globe A' may be of any convenient form. As shown the globe A' is adapted to rest upon the top of the lamp or fount B and to be moved vertically therefrom to light or to remove the 30 lamp. The Argand lamp B has the ordinary centrally-placed air-supply tube b. It is also provided with a perforate flange b' at its upper edge. As shown the flange b' is vertical and is turned inward to form a substantially 35 horizontal flange b² at its upper edge. Passing downward through the lamp B is an open-ended air passage or tube b³ secured, as by soldering, at the top and bottom of the lamp or fount. Three of such tubes b³ are shown in 40 Fig. 3; but it is evident that the number of these tubes is immaterial. Secured to the bottom of the fount B is a false bottom b⁴ enclosing an air space or passage from the tubes b³ to the central tube b. As shown the false 45 bottom b⁴ is of less diameter than the bottom 50

of the fount B, so that a shoulder is formed adapted to engage with the bottom plate of the lantern A. Resting upon the top of the fount B, within the flange b' and preferably removable, is the annular wind-guard C. 55 While the particular form of this guard is immaterial, I prefer to enlarge its lower portion c and to surmount a substantially vertical portion c' by a flange c². It is of importance that the lower edge of the guard C rests upon 60 the top of the fount B between the perforate flange b' and the upper ends of the air-tubes b³ and that ample space is afforded between the inner edge of the flange b² or between the lower edge of the globe A' and the body of 65 the guard C for the passage of air.

The operation of my device will be readily understood from an inspection of the drawings. It will be seen that the lantern-globe is supported by the flange b', so that the air 70 required to support combustion and to prevent overheating within the globe is drawn through the perforations in the flange. So much of this air as is required to support combustion passes over the wind-guard C. Part of 75 this supply passes through the ordinary perforations in the outer skirt of the burner to the outer mantle of the flame, while the rest is drawn downward through the tubes b³, between the true and the false bottom b⁴ of the 80 fount, and upward through the tube b to the inner mantle of the flame. The horizontal flanges b² and c², either or both of which may be advantageously employed in most forms of 85 my device, assist in controlling the air passing through the perforations in the flange b' and in preventing any disturbance of the flame. It is found in practice that a considerable increase in wind velocity does not alter the proportions of the air fed to the outer and inner 90 mantles of the flame, neither does such increase add to any disturbing extent to the volume of air supplied, as the excess entering at the windward side of the flange b' passes out at the other side. 95

It is clear that my device is capable of adaptation to lanterns of other style and shape than that shown and that many mechanical alterations may be made in my device without departing from my invention. 100

What I claim as my invention, and desire to secure by Letters Patent of the United States, is as follows:

1. In a lantern in combination an oil-fount, 5 a burner in said fount, a globe, a plurality of apertures for the admission of air between said fount and said globe, an air-chamber beneath said fount, a tube for the passage of air downward through said fount to said air-chamber and a 10 central air-supply tube for the upward passage of air from said air-chamber to said burner, said air-chamber being otherwise imperforate, substantially as described.
2. In a lantern in combination an oil-fount, 15

a burner in said fount, a globe, a flange perforated for the admission of air between said fount and said globe, a wind-guard surrounding said burner, an air-chamber beneath said fount, a tube for the passage of air downward through said fount to said air-chamber and a 20 central air-supply tube for the upward passage of air from said air-chamber to said burner, said air-chamber being otherwise imperforate, substantially as described.

THOMAS LANGSTON.
